UNITED STATES PATENT OFFICE.

WILLIAM C. SCHROEDER, OF LA PORTE, INDIANA, ASSIGNOR TO BENJAMIN L. ARMSTRONG, OF NEW LONDON, CONNECTICUT.

THREAD-PACKAGE.

SPECIFICATION forming part of Letters Patent No. 546,123, dated September 10, 1895.

Application filed June 11, 1895. Serial No. 552,386. (No model.)

To all whom it may concern:

Be it known that I, WILLIAM C. SCHROEDER, of La Porte, in the county of La Porte and State of Indiana, have invented a new and useful Improvement in Thread-Packages, of which the following is a specification.

My invention relates to an improvement in thread-packages, in which provision is made for inclosing a skein of silk or other thread within the casing, and providing a smooth and efficient bearing over which the threads of the skein may be drawn when it is desired to use them.

A practical embodiment of my invention is represented in the accompanying drawings, in which—

Figure 1 represents the casing as it appears when spread out in sheet form before being folded. Fig. 2 represents the bearing-piece partially folded. Fig. 3 represents the bearing-piece completely folded and the skein of thread located in position therein. Fig. 4 represents the casing folded to conceal the skein as in use. Fig. 5 represents the bearing-piece formed separate from the body portion and attached thereto by some suitable gum, and Fig. 6 represents a bearing-piece with broadened base.

The body portion of the casing consists, in the present instance, of a back A and side flaps or wings A' A'', the latter being in the present instance provided with a gummed face or edge for the purpose of sealing the package after the skein has been inserted.

The bearing-piece is preferably formed by a continuation of the back piece A, forming an extension a, having wings a' a'' severed from the wings A' A'' and adapted to be folded the one over the other toward the extended back a. When so folded, the extension a, together with its folded wings, is first folded downwardly into engagement with the inner face of the back A, and its end is then folded over, forming a bight a³, within which the skein B is to be received, and which serves to separate the opposite sides of the skein and form a bearing for the withdrawal of the threads of the skein, as may be required.

After the last fold has been made the flaps

A' and A'' of the body of the casing are folded the one over the other, and the extended end of the bearing-piece is finally folded downwardly over the folded flaps A' A'' and either left free or secured by some suitable gum to the body, as desired. The opposite end of the skein from that which is received on the bearing-piece is preferably permitted to extend from the casing, as shown at b, and may be provided with a tag b', which conveniently serves the purpose of separating the opposite sides of the skein from one another at that end.

The bearing-piece hereinbefore described has the advantage of being reinforced by the folded end flaps of the extension, so that its edges are smooth and sufficiently rounded to prevent any liability of the threads being chafed or cutting out the bearing as they are withdrawn therefrom. The bearing itself is also inclosed within the sides of the casing, forming a complete protection for the end of the skein, and if the extreme end of the bearing-piece be not secured to the casing it will admit of being withdrawn from within the casing in case there should be a desire to get at that end of the skein.

It is obvious that the bearing-piece might be formed separate and secured to the end of the body of the casing, as shown in Fig. 5, instead of being formed integral with the body of the casing, but the integral form is found preferable in practice.

The bearing-piece represented by a², Fig. 6, has its base cut on a slant, so that the fold extends onto the wings, and they assist in resisting the strain when the thread is pulled.

What I claim is—

1. A thread package, comprising a folded body portion, an end portion reinforced by folded flaps and further folded within the end of the casing, forming a bearing over which the threads of the skein may be withdrawn from the package, substantially as set forth.

2. The thread package, comprising the folded body portion and the end portion formed integral with the body portion and reinforced by folded flaps, the said end portion being further folded within the end of the casing to form a bearing over which the

threads of the skein may be withdrawn, substantially as set forth.

3. The thread package, comprising the folded body portion, and the end portion reinforced by folded flaps, the said end portion having a fold within the end of the body of the casing as the bearing for the end of the

skein and a further fold over the end of one side of the body portion, substantially as set forth.

WILLIAM C. SCHROEDER.
